(57) **CLAIM**

The ornamental design for a microfluidic chip for use with a fluid perfusion module, as shown and described.

DESCRIPTION

FIG. 1 is a top plan view of an ornamental microfluidic chip. FIG. 2, is a bottom plan view, thereof.

FIG. 3 is a left side elevational view, thereof.

FIG. 4 is a right side elevational view, thereof.

FIG. 5 is a front side elevational view, thereof.

FIG. 6 is a rear side elevational view, thereof; and,

FIG. 7 is a top perspective view, thereof.
